Primary Examiner — Ian Simmons*Assistant Examiner* — Rhea Shields(74) *Attorney, Agent, or Firm* — Husch Blackwell LLP(57) **CLAIM**

The ornamental design for a wine container, as shown and described.

DESCRIPTION

FIG. 1 is a perspective view of a wine container showing my new design;

FIG. 2 is a front elevation view thereof;

FIG. 3 is a rear elevation view thereof;

FIG. 4 is a right side elevation view thereof;

FIG. 5 is left side elevation view thereof;

FIG. 6 is a top plan view thereof; and,

FIG. 7 is a bottom plan view thereof.

The stippling patterns shown in FIGS. 1 through 6 indicate a contrast in appearance.

1 Claim, 7 Drawing Sheets(56)
